DEGERMINATION PROCESS

Charles R. Brown, Champaign, Ill., assignor to
The Sharples Corporation, Philadelphia, Pa.,
a corporation of Delaware

Application April 22, 1936, Serial No. 75,730

7 Claims. (Cl. 83—42)

The present invention pertains to degermination of grains and particularly of corn. It is concerned with the performance of a sequence of steps by which the germ of the grain and particles other than the germ can be treated to effect a desired conditioning of said other particles and separation of the germ in a form in which its oil can be economically removed with a high degree of efficiency. It is particularly concerned with 5 a process of this character in which the particles of the grain other than the germ are obtained in a form in which they may be used in the cooking operation preliminary to the preparation of spirituous liquors of high quality.

15 In the conventional process of preparing starch, the whole grain is first steeped for a period varying between three and ten days in order to soften thoroughly the particles of grain surrounding the germ. At the conclusion of the steeping period, 20 the germ is removed from the grain by flotation in a body of aqueous starch liquid and treated separately from the grain. The hulls and starchy matter are first ground and then passed through a preliminary separating step in which fibrous 25 material is removed by means of screens, and the starch is produced from the liquor which passes through such screens. While such a process is satisfactory for the preparation of starch, it cannot be employed in the treatment of grain which 30 is to be used for the preparation of spirituous liquor because of bacterial contamination which occurs during the long steeping period or because of the undesired flavor imparted by preservatives used to prevent such bacterial contamination.

35 In the manufacture of grits and corn-meal, a so-called dry degerminating process is used. In the practice of such a process, the corn is first passed through a cracking mill. This cracking 40 mill breaks up the particles of corn surrounding the germ but it also breaks up the germ itself to a substantial extent. At the conclusion of the cracking operation, the cracked grain is subjected to a succession of screening and aspirating 45 operations designed to effect a certain degree of separation between germ particles and grits particles. Such an operation yields a grits fraction containing a much smaller proportion of germs than that contained in the original grain on the 50 one hand, and it yields on the other hand a germ fraction containing a larger proportion of germs than that contained in the original grain. The separation of grits from germs in such an operation cannot, however, be considered in any sense 55 efficient.

In distillery operations it is customary to utilize the whole grain and no attempt at preliminary separation of germ from other grain particles is ordinarily made prior to the cooking of the grain particles as the first step in the liquor manufacturing operation. Neither the wet degermination process first described above nor the dry degermination process just described has been adapted to a process of making whiskey, for example. The wet degermination is unsatisfactory, as stated above, because of bacterial contamination or undesired flavor of preservatives added incident to the steeping, and the dry degermination process is unsatisfactory because of the inadequate separation of germ from other grain particles and the lower yield of germ obtained in connection with such degermination.

10 The object of the present invention has been to devise a process of treatment of grain such as corn by which the grain may be degerminated with a high degree of efficiency and the particles of grain other than germ be utilized efficiently 15 in the manufacture of spirituous liquors. The manner in which this object and other objects of the invention are attained will be understood best by reference to the attached flow-sheet in which,

20 The single figure represents the steps of a steeping and degerminating operation performed in accordance with the principle of the invention.

25 Referring to the drawing by reference characters, the grain is first introduced into a steeping tank 10 and a vacuum is thereafter applied to the tank. Steeping liquor may be added prior to the application of vacuum, but the preferred 30 form of practice of the invention involves the application of vacuum to the grain prior to the introduction of steeping liquor. After the introduction of the grain, the tank is closed and the grain is subjected to a vacuum which is as high 35 as can conveniently be maintained, such for instance as 28" or 29" of mercury. The grain is thus subjected to the action of the vacuum for a period of time sufficient to remove the air present in the cells of the grain, usually about 40 thirty minutes.

45 After the grain has been de-aerated to the desired degree, it is covered with water. After the grain has been covered with water, the interior of the steeping tank is vented to the atmosphere, 50 the de-aerated grain being thus subjected to the atmospheric pressure plus pressure due to the head of the water. The effect of this sequence of operations is to force the water into the de-aerated grain. By reason of the de-aeration prior 55

to the steeping operation, it is possible to soften the grain to the desired extent in the steeping step in a period varying between three and twelve hours, as contrasted with the period of three to 5 ten days required in the prior practice.

In the practice of the present invention, the respective specific gravities of the materials obtained by cracking the steeped grain are such as to render the practice of the prior art wet de- 10 germinating process exceedingly difficult. The problem of effecting a separation of germ from other grain particles can be solved by the process of my prior application Serial No. 49,494, filed November 13, 1935, entitled "Steeping and deger- 15 minating process." The process of that application, however, is relatively expensive and involved, and a result as good as that achieved by the prior process is achieved in the practice of the present invention much more simply and 20 economically.

In the illustrated embodiment of the practice of the present invention the grain steeped in receptacle 10 is first passed to a screen 11 through which the major part of its water is drained 25 and removed. The partially dried grain is then passed to a dry cracking mill 12 which is designed to perform a rough cracking operation upon the particles of grain surrounding the germ without breaking the germ particles. The 30 cracked grain from the mill 12 is next subjected to a series of screening and aspirating operations of a type known per se in the art of dry degermination but not, so far as I am aware, heretofore practiced in the art of separating germs from other grain particles obtained by the vacuum steeping process described above.

The flow sheet illustrates one example of a 40 sequence of screening and aspirating steps constituting steps of the process of the present invention following the cracking operation in the mill 12. In this flow sheet, the material from the mill 12 is first passed to a screen 13 which may be provided with square perforations with 45 sides having lengths of $1\frac{1}{4}$ ths inch each. The bulk of the starchy constituents of the grain and the germ particles pass through the screen 13 to a ten mesh screen 14. Uncracked grains and imperfectly cracked grains and large hull 50 particles pass from the screen 13 as tailings to an aspirator 15. This aspirator effects separation of a large part of the hulls from other grain particles by sucking hulls upwardly and the particles not sucked upwardly are returned 55 to the cracking operation. The hulls sucked upwardly by the aspirator 15 are passed ultimately to the cookers of the distillery process in a manner to be described hereinafter.

The screen 14 allows starchy particles to pass 60 therethrough, but passes germ particles and larger particles of grain as tailings to the aspirator 16. This aspirator 16 sucks hull particles upwardly and allows germs and the bulk of the starchy ingredients passing as tailings 65 from the screen 14 to drop to a dryer 17. The material passed to the dryer 17 is subjected to a drying operation in which its moisture content is reduced to 25%. The material from the dryer 17 is next passed to a screen 18 which 70 may be provided with round perforations having diameters of $1\frac{1}{4}$ ths inch. The drying of the material in the dryer 17 effects a shrinkage of the germs subjected to the drying operation and these germs pass through the screen 18 to 75 a six mesh screen 19. The tailings from the

screen 18 may be returned to the cracking operation as illustrated.

The screen 19 allows fine particles to pass therethrough and the tailings from this screen, consisting of germs and large grain particles 5 pass to the aspirator 20. This aspirator sucks hulls upwardly and allows the germs and other grain particles to pass downwardly. The particles passed through the screen 19 are subjected to a further screening operation upon the screen 21. The tailings from the screen 21 are passed to an aspirator 22 which effects a separation between hulls and other constituents of the grain similar to the separating function of the aspirators described above. The heavier constituents 15 consisting of germs and other grain particles which drop downwardly from the aspirators 20 and 22 are passed to separate double roller mills 23 and 28. These roller mills are designed to effect a cracking operation upon grain particles 20 other than germs passing therethrough and to flatten the germs without cracking them. The rolls of the mill 28 are spaced together more closely than are the rolls of the mill 23.

The material which passes through the rolls 25 23 is subjected to a further screening operation by the screen 24 and the tailings from this screen are subjected to a further aspirating operation by the aspirator 25. The material passing through the screen 24 is subjected to a further screening operation by the screen 26 and to a further aspirating operation by the aspirator 27.

Material passing downwardly from the aspirator 27 is passed, together with similar material 35 from the aspirator 22, through the double roller mill 28 and thence to screen 29. The tailings from the screen 29 are further aspirated at 30. The germ particles separated from other constituents of the grain in aspirators 25 and 30 40 pass to a dryer 32 and thence to an oil recovery operation. As illustrated, this operation is performed by an expeller press 33. The cake from the expeller press is passed through a breaker 34 and thence through a mill 31. Grain particles sucked upwardly by the aspirators 15, 16, 20, 22, 25, 27, and 30 are passed with the expeller cake through the mill 31 and thence to the cookers employed in the further processing of these particles to produce alcoholic products. 50 The fine material passing through the screens 14, 21, 26 and 29 is likewise passed to the cookers.

It will be seen that the practice of the invention involves an efficient separation of germs from other constituents of the grain and that 55 the vegetable oil may accordingly be separated from the germs. Since the cake from the expeller press as well as the grain particles separated upwardly by the aspirators is passed to the cookers, no material useful to the alcohol 60 manufacturing operation is lost. The net result of the practice of the process is therefore to obtain extraction of the vegetable oil from the germs of the grain without any corresponding loss.

Modifications will be obvious to those skilled in the art and I do not therefore wish to be limited except by the scope of the subjoined claims.

I claim:

1. The process of treating germ-containing 70 grain which comprises placing the grain in a container, removing air from said container to create a substantial vacuum within the interstices of said grain, covering the grain with a steeping liquid, subjecting this liquid to atmos-

pheric pressure and thereby increasing the pressure under which the grain is maintained, subjecting the grain to the steeping effect of the liquid for a number of hours, the degree of the 5 vacuum, the pressure subsequently applied, and the duration of the steeping being so inter-related as to effect thorough softening of the starch constituents of the grain without extracting a large proportion of the material contained in the 10 germs, so that the germs retain many of their ingredients which have relatively high specific gravity and the starch-containing fraction of the grain remains substantially free of bacterial contamination, disintegrating the starch by 15 cracking the outer constituents of the steeped grain without cracking the germs and finally separating cracked grain particles from germs by a sequence of screening and aspirating operations.

10. 2. The process of treating germ-containing grain which comprises placing the grain in a container, removing air from said container to create a substantial vacuum within the interstices of said grain, covering the grain with a 25 steeping liquid, subjecting this liquid to atmospheric pressure and thereby increasing the pressure under which the grain is maintained, subjecting the grain to the steeping effect of the liquid for a period of time between approximately 30 three and twelve hours, the degree of the vacuum, the pressure subsequently applied, and the duration of the steeping being so inter-related as to effect thorough softening of the starch constituents of the grain without extracting a large 35 proportion of the material contained in the germs, so that the germs retain many of their ingredients which have relatively high specific gravity and the starch-containing fraction of the grain remains substantially free of bacterial 40 contamination, disintegrating the starch by cracking the outer constituents of the steeped grain without cracking the germs and finally separating cracked grain particles from germs by a sequence of screening and aspirating operations.

15. 3. The process of treating germ-containing grain which comprises placing the grain in a container, removing air from said container to create a substantial vacuum within the interstices of said grain, covering the grain with a steeping liquid, subjecting this liquid to atmospheric pressure and thereby increasing the pressure under which the grain is maintained, subjecting the grain to the steeping effect of the liquid for a period of time between approximately 50 three and twelve hours, the degree of the vacuum, the pressure subsequently applied, and the duration of the steeping being so inter-related as to effect thorough softening of the starch 55 constituents of the grain without extracting a large proportion of the material contained in the germs, so that the germs retain many of their ingredients which have relatively high specific gravity and the starch-containing fraction of the grain remains substantially free of bacterial 60 contamination, disintegrating the starch by cracking the outer constituents of the steeped grain without cracking the germs, separating cracked grain particles from germs by a sequence of screening and aspirating operations, subjecting the germs and contaminating grain particles 65 after said sequence of said screening and aspirating operations to the application of pressure between rollers to effect breaking of grain particles other than germs and flattening of germs, and finally subjecting materials passed through said rollers to a further sequence of screening and aspirating operations.

70. 4. The process of treating germ-containing grain which comprises placing the grain in a container, removing air from said container to create a substantial vacuum within the interstices of said grain, covering the grain with a steeping liquid, subjecting this liquid to atmospheric pressure and thereby increasing the pressure under which the grain is maintained, sub-

finally subjecting materials passed through said rollers to a further screening operation.

5. The process of treating germ-containing grain which comprises placing the grain in a container, removing air from said container to create a substantial vacuum within the interstices of said grain, covering the grain with a steeping liquid, subjecting this liquid to atmospheric pressure and thereby increasing the pressure under which the grain is maintained, subjecting the grain to the steeping effect of the liquid for a period of time between approximately three and twelve hours, the degree of the vacuum, the pressure subsequently applied, and the duration of the steeping being so inter-related as to effect thorough softening of the starch constituents of the grain without extracting a large proportion of the material contained in the germs, so that the germs retain many of their ingredients which have relatively high specific gravity and the starch-containing fraction of the grain remains substantially free of bacterial contamination, disintegrating the starch by cracking the outer constituents of the steeped grain without cracking the germs, separating cracked grain particles from germs by a sequence of screening and aspirating operations, subjecting the germs and contaminating grain particles after said sequence of said screening and aspirating operations to the application of pressure between rollers to effect breaking of grain particles other than germs and flattening of germs, and finally subjecting materials passed through said rollers to a further aspirating operation.

6. The process of treating germ-containing grain which comprises placing the grain in a container, removing air from said container to create a substantial vacuum within the interstices of said grain, covering the grain with a steeping liquid, subjecting this liquid to atmospheric pressure and thereby increasing the pressure under which the grain is maintained, subjecting the grain to the steeping effect of the liquid for a period of time between approximately three and twelve hours, the degree of the vacuum, the pressure subsequently applied, and the duration of the steeping being so inter-related as to effect thorough softening of the starch constituents of the grain without extracting a large proportion of the material contained in the germs, so that the germs retain many of their ingredients which have relatively high specific gravity and the starch-containing fraction of the grain remains substantially free of bacterial contamination, disintegrating the starch by cracking the outer constituents of the steeped grain without cracking the germs, separating cracked grain particles from germs by a sequence of screening and aspirating operations, subjecting the germs and contaminating grain particles after said sequence of said screening and aspirating operations to the application of pressure between rollers to effect breaking of grain particles other than germs and flattening of germs, and finally subjecting materials passed through said rollers to a further sequence of screening and aspirating operations.

75. 7. The process of treating germ-containing grain which comprises placing the grain in a container, removing air from said container to create a substantial vacuum within the interstices of said grain, covering the grain with a steeping liquid, subjecting this liquid to atmospheric pressure and thereby increasing the pressure under which the grain is maintained, sub-

- jecting the grain to the steeping effect of the liquid for a period of time between approximately three and twelve hours, the degree of the vacuum, the pressure subsequently applied, and the duration of the steeping being so inter-related as to effect thorough softening of the starch constituents of the grain without extracting a large proportion of the material contained in the germs, so that the germs retain many of their ingredients which have relatively high specific gravity and the starch-containing fraction of the grain remains substantially free of bacterial contamination, disintegrating the starch by cracking the outer constituents of the steeped grain without cracking the germs, separating cracked grain particles from germs by a sequence of screening and aspirating operations, expelling moisture from the germ particles together with other grain particles separated with the germ particles in said last-mentioned sequence of screening and aspirating operations.
7. The process of treating germ-containing

grain which comprises placing the grain in a container, removing air from said container to create a substantial vacuum within the interstices of said grain, covering the grain with a steeping liquid, subjecting this liquid to a pressure sufficient to cause the steeping liquid to penetrate the grain, subjecting the grain to the steeping effect of the liquid for a period of time between approximately three and twelve hours, the degree of the vacuum, the pressure subsequently applied, and the duration of the steeping being so inter-related as to effect thorough softening of the starch constituents of the grain without extracting a large proportion of the material contained in the germs, so that the germs retain many of their ingredients which have relatively high specific gravity and the starch-containing fraction of the grain remains substantially free of bacterial contamination, disintegrating the starch by cracking the outer constituents of the steeped grain without cracking the germs and finally separating cracked grain particles from germs by a sequence of screening and aspirating operations.

CHARLES R. BROWN. 23
